UNITED STATES PATENT OFFICE.

ALFRED H. WORREST, OF LANCASTER, PENNSYLVANIA.

DESIGN FOR A BODY-HANGER FOR VEHICLES.

SPECIFICATION forming part of Design No. 35,393, dated December 3, 1901.

Application filed April 24, 1901. Serial No. 57,346. Term of patent 14 years.

To all whom it may concern:

Be it known that I, ALFRED H. WORREST, a citizen of the United States, residing at Lancaster, in the county of Lancaster and State 5 of Pennsylvania, have invented and produced a new and original Design for Body-Hangers for Vehicles, of which the following is a specification, reference being had to the accompanying drawings, forming part thereof.

10 Figure 1 is a perspective view of a body-hanger embodying my design; Fig. 2, a top plan view, and Fig. 3 a rear elevation thereof.

15 As shown in the drawings, the leading or material feature of my design consists of a spring-bar A, arms on the ends of spring-bar A, the initial direction whereof is a prolongation of the spring-bar, as at a, and turned inward with a short curve, as at b, to a line 20 approximately parallel with spring-bar A, then turned outwardly and downwardly in a

vertical plane approximately parallel with the vertical longitudinal plane of spring-bar A, as at d, and downward, and then again curved backward from the direction of spring-bar A, as at f, and terminating in approximately horizontal extensions B. The ends of horizontal extensions B are flattened, as at g, and terminate in reduced extensions h.

Having described my invention, what I claim as new, and desire to secure by Letters 25 Patent, is—

The design for a body-hanger for vehicles, as herein shown and described.

In testimony whereof I have signed my name to this specification in the presence of 30 two subscribing witnesses.

ALFRED H. WORREST.

Witnesses:

C. G. BASSLER,
WM. R. GERHART.
